UNITED STATES PATENT OFFICE.

JAMES C. HOSFORD, OF MALDEN, MASSACHUSETTS, ASSIGNOR TO MAGEE FURNACE CO., OF BOSTON, MASSACHUSETTS, A CORPORATION.

DESIGN FOR A STOVE.

No. 38,893.

Specification for Design.

Patented Nov. 19, 1907.

Application filed October 7, 1907. Serial No. 396,355. Term of patent 7 years.

To all whom it may concern:

Be it known that I, JAMES C. HOSFORD, a citizen of the United States, residing at Malden, in the county of Middlesex and State of Massachusetts, have invented a new, original, and ornamental Design for Stoves, of which the following is a specification, reference being had to the accompanying drawing, forming a part thereof.

The figure is a view in perspective of a stove, showing my new design.

I claim

The ornamental design for a stove as shown.

JAMES C. HOSFORD.
